UNITED STATES PATENT OFFICE.

HENRY C. SEARS, OF BOSTON, MASSACHUSETTS.

DESIGN FOR A CARRIAGE-BODY.

SPECIFICATION forming part of Design No. 26,347, dated November 24, 1896.

Application filed November 26, 1895. Serial No. 570,116. Term of patent 14 years.

To all whom it may concern:

Be it known that I, HENRY C. SEARS, a citizen of the United States, residing at Boston, in the county of Suffolk and State of Massachusetts, have invented and produced a new and original Design for Carriage-Bodies, of which the following is a specification, reference being had to the accompanying drawings, forming part thereof, and in which—

10 Figure 1 is a view in side elevation of the body of a two-wheeled carriage embracing my design, and Fig. 2 shows my design adapted for the body of a four-wheeled carriage.

15 The leading feature of my design is the form and ornamentation of the sides of the carriage-body, and more particularly with reference to the lower parts and front corners of the sides.

20 The side of the vehicle is divided by horizontal molding a into the lower panel A and the upper section A', and the lower panel A is separated by the vertical pillar B into the sections a' a'' . The section a'' of the panel is set in somewhat as compared with the section 25 a' , and it has a curved outer edge or molding b , which extends from the pillar at b' to the foot-board. The section a' of the panel is bounded upon its upper edge by the horizontal molding a , having a slight upward curve,

and by the rear molding a^3 , which extends 30 from the rear end a^4 of the molding downwardly and forwardly upon a curved line to the point a^5 , where it again drops and rises on a curved line, uniting at a^6 , in the form of a scroll, with the curved lower end b^2 of the 35 pillar B. The pillar forms also the front b^3 of the upper section A' of the side, being substantially perpendicular from the point b^4 to the point b^5 , where it curves forward on a horizontal curve to the scroll b^6 at the end of 40 the overhanging section b^7 of the section A'. This section has upon its side the ornamental device C and the ornamental rim D about a glass d.

Having thus fully described my invention, 45 I claim and desire to secure by Letters Patent of the United States—

1. The design for a carriage-body as herein described and shown.
2. In a design for a carriage-body, the pattern which comprises the moldings or beads a , a^3 and b , pillar B and scroll a^6 , of the conformation shown, and collectively forming the panels a' and a'' , as set forth.

HENRY C. SEARS.
